CLAIM

The ornamental design for a proppant vessel base, as shown and described.

DESCRIPTION

FIG. 1 is an upper perspective view of the proppant vessel base [showing] embodying our new design[.];

FIG. 2 is a front [elevation] elevational view [thereof] of the embodiment of FIG. 1;

FIG. 3 is a rear [elevation] elevational view [thereof] of the embodiment of FIG. 1;

FIG. 4 is a right side [elevation] elevational view [thereof] of the embodiment of FIG. 1;

FIG. 5 is [an opposite] a left [elevation] elevational view [thereof] of the embodiment of FIG. 1;

FIG. 6 is a top plan view [thereof] of the embodiment of FIG. 1; and,

FIG. 7 is a bottom plan view [thereof] of the embodiment of FIG. 1.

[The features presented in broken lines are for environmental purposes only and form no part of the claimed design.]
The broken lines depict portions of the proppant vessel in which the design is embodied that are not considered part of the claimed design.
